PORTABLE BACK SUPPORT FOR SEATS

Harold H. Cooper, Tulsa, Okla.

Application December 30, 1937, Serial No. 182,579

4 Claims. (Cl. 155—133)

This invention relates to seats and particularly to a portable back support designed for use in stadiums, on bleacher seats and under like circumstances.

5 The general object of the invention is to provide a very simple, sturdily made and readily portable back support having means whereby it may be engaged with a stadium or bleacher seat or bench, and which is so constructed that the 10 seat engaging portion may be folded up against the back support when not desired for use.

A further object is to so connect the seat engaging element with the back support that the hinged joint between the seat engaging element 15 and the back support will not pinch or snag the garments of the wearer.

My invention is illustrated in the accompanying drawing wherein:

Fig. 1 is a front elevation of my device in position on a seat.

Fig. 2 is a vertical section on the line 2—2 of Fig. 1.

Fig. 3 is a fragmentary section on the line 3—3 of Fig. 2 on an enlarged scale.

25 Fig. 4 is a fragmentary vertical sectional view through one of the side bars of the back support showing the means whereby the back support is pivotally connected to the seat engaging element.

Fig. 5 is an elevation of the structure shown in 30 Fig. 4, the seat engaging element being shown in section.

Referring to the drawing, 10 designates a metallic back support which is shown as approximately U-shaped to provide lateral downwardly 35 extending side portions 11. The upper portion of this back support is filled in by a web 12, which may be made of metal, fabric, leather or any other suitable material. As will be seen from Fig. 2, the frame 10 with the downwardly extending portions or legs 11 is approximately U-shaped in cross-section and the web 12 at its upper portion is extended forward and is attached to the front flange 13 of the frame 10. The front flange at its lower end is cut away, as 40 shown in Fig. 4, and bent forwardly, as at 14.

The back support is engaged with the seat A of a bleacher or stadium seat by means of a seat engaging element designated generally 15, which comprises two side bars 16, each side bar 50 at its forward end extending downward, as at 17, and then inward or rearward, as at 18, and terminating in a cross-bar 19, which connects the two inwardly extending portions 18. Thus the seat engaging element is formed at its forward 55 end with a hook which engages beneath the for-

ward edge of the seat A and holds the back supporting frame in place upon the seat. Each of the bars 16 extends rearwardly, as shown in Fig. 4, and at its rear end is bent around at 20, to form an eye. This eye is pivoted to the lower 5 end of the corresponding member 11 of the back, as will be now described.

Embracing each bar 16 at its rear end is a triangular shield 21, which is folded along its lower edge to extend beneath and fit against and partly 10 embrace the rear end of the corresponding seat engaging bar the corresponding bar 16 and upward on each side of the corresponding portion 11 of the back frame 10, as shown clearly in Figs. 4 and 5. This shield is triangular in side elevation and the lateral members of the shield are inwardly flanged at 22 to extend over the rear face of the corresponding member 11. A rivet 23 passes through the member 11 and through the two side walls of the shield, as shown in Figs. 3 20 and 5, and a rivet 24 extends through the side walls of the shield, through the eye 20 and through the forwardly bent flange 14, thus pivotally connecting the element 15 with the back frame. It will be understood that the triangular 25 shield is thus rigidly held to the legs 11 of the back frame but that the back frame may be turned down against the seat engaging element 15, as shown by dotted lines in Fig. 4. The purpose of bending the flange 11 forwardly, as at 30 14, is to provide a suitable bearing for the rivet 24, which constitutes the pivot and to provide clearance for the eye 20, and one purpose of the triangular shield is to prevent any possibility of the clothes of the user becoming pinched or 35 snagged at the hinge joint between the element 16 and the back frame 10. A further and important feature of this triangular member 21 is to constitute means for supporting the back of the seat when the back is placed in a vertical position and receives the pressure of the user's back. Under these circumstances, the member 21 transmits the backward thrust on the back of the seat to the bars 15 and they carry the ultimate strain to the hooks 18. Still another important feature 40 45 incident to the use of the shields 21 is that these shields prevent the back 10 from being forced down against the bars 15 when these bars are engaged with the bleacher seat A. This advantage is secured by folding the material for each triangular shield along the lower edge of the shield so that this folded portion fits closely against the corresponding bar 16 and is disposed between the corresponding bar 16 and the slats of the bleacher seat. Thus if the user of the back support should 50 55

- rise for any reason, the back cannot be thrown down by a person sitting in the next rearward seat because inasmuch as the back 10 is rigidly connected to the triangular shields, these triangular shields would have to be forced down if the back is turned down. This would act to lift the side bars 16 at their rear ends but this in turn is prevented by the hooks 18 which bear against the underface of the forward slat of the 10 bleacher seat so that until the back support is entirely removed from the slats of the bleacher seat A, the back cannot be turned down either accidentally or intentionally by a person sitting behind nor can it accidentally fall down.
- 15 The back 12 is dished out to fit the body and may be used with or without a cushion as desired, it being preferably made to form-fitting shape similar to the rounded or concave back of certain chair backs.
- 20 I do not wish to be limited to the use of channel irons 11 as this back frame 10 might be formed of small pipe, a rod rounded in cross-section or an angle iron, as may be found desirable.
- 25 What is claimed is:—
1. A device of the character described, including a back frame having two laterally spaced downwardly extending side bars and a connecting portion, a seat engaging element having two laterally spaced bars pivoted at their rear ends to the lower ends of the back bars, the seat engaging element at its forward end being formed with a hook to engage beneath the forward edge of a seat, and a triangular shield folded along its lower edge to receive, fit against and partially embrace the rear end of the corresponding seat engaging bar and extending upwardly on opposite sides of the corresponding side bar of the back and extending partly over the rear edge of the corresponding side bar, said shield being rigidly attached to the side bars of the back.
  2. A device of the character described, including a back support formed of channel iron and bent to provide two laterally spaced downwardly extending side bars and a connecting portion, the flanges of said channel iron extending inwardly, the forward flange of each channel iron at its lower end being bent forwardly, a seat engaging element having two laterally spaced bars connected to each other at their forward ends by a cross-bar, the laterally spaced bars of the seat engaging element being bent to form eyes at their rear ends, triangular shields each extending beneath and embracing the rear end of each seat engaging bar and extending up on opposite sides of the corresponding side bar of the back, a rivet engaging the upper end of each shield with the corresponding side bar of the back, and a rivet passing through the shield, through said eye in the corresponding seat engaging bar and through the forwardly extending flange of the corresponding side bar of the back.

the seat engaging element being bent to form eyes at their rear ends, triangular shields each extending beneath and embracing the rear end of each seat engaging bar and extending up on opposite sides of the corresponding side bar of the back, a rivet engaging the upper end of each shield with the corresponding side bar of the back, and a rivet passing through the shield, through said eye in the corresponding seat engaging bar and through the forwardly extending flange of the corresponding side bar of the back.

3. A device of the character described, including a back support formed of channel iron and bent to provide two laterally spaced downwardly extending side bars and a connecting portion, the flanges of said channel iron extending laterally inwardly, the forward flange of each channel iron at its lower end being bent forwardly, a seat engaging element having two laterally spaced bars connected to each other at their forward ends by a cross-bar, the laterally spaced bars of the seat engaging element being bent to form eyes at their rear ends, triangular shields, each extending beneath and embracing the rear end of a corresponding seat engaging bar and extending up on opposite sides of the corresponding side bar of the back, a rivet engaging the upper end of each shield with the corresponding side bar of the back, and a rivet passing through each shield, through said eye in the corresponding seat engaging bar and through the forwardly extending flange of the corresponding side bar of the back, the forward end of each seat engaging bar being extended downwardly and rearwardly and said rearwardly extending ends being connected by the cross-bar.

4. A device of the character described, including a back supporting frame having two laterally spaced side bars and a connecting portion, a seat engaging element including two laterally spaced bars, the element having means at its forward end for engaging beneath the forward edge of a seat and triangular shields, each folded along its lower edge to partially embrace and fit against the underface of the rear end of the corresponding seat engaging bar and extend upwardly on opposite sides of the corresponding side bar of the back and rigidly attached thereto, the seat engaging element being pivoted to the side bars of the back and to said shields.
